UNITED STATES PATENT OFFICE.

CLARENCE A. DAWLEY, OF PLAINFIELD, NEW JERSEY.

SEPARATOR AND TRAP.

Application filed November 1, 1923. Serial No. 672,105.

To all whom it may concern:

Be it known that I, CLARENCE A. DAWLEY, a citizen of the United States of America, residing at Plainfield, in the county of Union and State of New Jersey, have invented certain new and useful Improvements in Separators and Traps, of which the following is a specification.

My invention relates to a combined separator and trap for automatically removing moisture from a gaseous fluid flowing under pressure through a pipe, and for collecting and discharging the entrained liquid and such solids as may be carried into the apparatus by the gas. The object of my invention is to provide an improved device of this general type which is simple in construction, compact, light, inexpensive and free from operating troubles, and having certain other advantages hereinafter explained or apparent from the accompanying drawings, in which—

Fig. 1 is a vertical section through an apparatus embodying my invention in one form;

Fig. 2 is a section on the line A—A, Fig. 1;
Fig. 3 is a section on the line B—B, Fig. 1;
Fig. 4 is a section on the line C—C, Fig. 1;

Fig. 5 is a broken plan of the valve frame.

While the present separator and trap may be employed for any appropriate use, it is designed particularly for compressed air lines, and serves to remove the moisture from the air passing through the pipes. However, I use the expression "gas" herein-after in a sense broad enough to cover steam, air or other moist gaseous fluid. It will be understood furthermore that the construction shown is but an illustrative embodiment of my invention, and that various modifications may be made in the construction and arrangement of parts, which embody what I claim as my invention.

Referring to the drawing, the device shown comprises a head casting 1 which rests upon a body casting 2, to the lower portion of which is applied a lateral valve housing or cap plate 3, the several castings being secured together by any appropriate means to form a closed chamber.

The head casting 1 is provided with an inlet port 4 and an outlet port 5, both tapped to receive respectively inlet and outlet pipes (not shown). Arranged within the head is a transversely extending baffle plate 6 which

may be cast integral with the head or formed as an independent member secured thereto, as shown, by one or more bolts 7 passing through the top of the head casting. The baffle plate extends only partially across the head of the chamber, and is provided with vertical side flanges 8 and 9 arranged at an acute angle to the baffle plate and faced toward the inlet port 4. At its lower margin the baffle plate is oppositely and downwardly inclined toward a central drainage aperture 10. Gutter flanges 11 and 12, upwardly inclined from the lower margins of the baffle plate lead to the aperture 10. A top flange 13 may be provided for the reception of the securing bolts 7 when the baffle is formed independently of the head casting.

Carried by the baffle plate and faced toward the inlet port 4, is a V-shaped deflecting screen 14 preferably formed from spring sheet metal pierced by apertures 15. While the deflector may be mounted and secured in position solely by the gutter flanges 11 and 12, and through its spring engagement in the corners afforded by the inwardly inclined side flanges 8 and 9, I prefer to attach it permanently to the baffle by brazing, soldering, or the like. In operation, the gas and water entering at inlet 4 strike the perforated deflector 14; the water being heavier tends to pass through the perforations 15 and drops down into the space between the deflector and baffle 6 onto the drip plate 16, and passes out through the drainage aperture 10.

Underlying the baffle plate 6 I arrange a channelled drip plate 16 secured in any suitable way to the gutter flanges 11 and 12 and inclined downwardly from intake to outlet end of the baffle chamber. The drip plate is substantially coextensive with the area of the baffle chamber and thus tends to confine the turbulent flow of the gas to the baffle chamber. The gas in the portion of the chamber below the drip plate is thus maintained substantially stagnant. In other words, the gas flowing through the apparatus does not come in contact with the liquid accumulated in the trap, and consequently does not tend to again pick up the moisture which it loses at the baffles.

To cause further changes of direction in the gas as it passes through the baffle chamber, ribs 17 and 18 may be provided projecting inwardly from the wall of the head casting adjacent the outlet connection 5.

Such moisture as is deposited on these ribs falls upon the drip plate 16 and is discharged at the lower margin of the latter. It will be noted that the discharge from the drip plate takes place adjacent one side of the body 2 forming the trap chamber, and clears the float 19 arranged therein.

A further separating action results from the fact that the "center of area" of the lateral passages around the baffle plate 6 is materially lower than the center line of the inlet and outlet ports 4 and 5. As the gas rises to the outlet 5 after passing the baffle 6, the heavier liquid particles sink and flow down the drip plate 16 into the trap.

The lateral valve plate 3 for the trap is provided with an outwardly projecting hollow boss 20 apertured at its outer end to accommodate the threaded and longitudinally pierced stem 21 of the valve frame 22. Supported within the valve frame is the horizontal valve stem 23 adapted to close and open the port at the inner end of the stem 21. This port communicates with a transverse channel 24 formed in the valve frame and opening to the interior of the boss 20.

Pivottally mounted at 25 upon the upper web of the valve frame is a double-arm, bell-crank float lever 26, one end of which embraces and is secured to the float 19. The other end 27 straddles the valve stem 23 and is engaged between collars 28 thereon to open or close the valve with the rise or fall of the float. The valve frame and its associated parts are secured in position within the boss 20 by a nut 29 threaded on the projecting end of stem 21 of the frame, and are held against rotation by a stud 30 taking into a channel 31 in the boss.

The arrangement of the outlet channel 24 adjacent the outer end of the boss 20 serves to prevent clogging of the valve port by solids or sediment in the trap, the location of the boss being sufficiently above the bottom of the trap to afford ample space for the accommodation of solids. One or more clean-out openings 32 may be formed adjacent the bottom of the body casting 2 through which, upon the removal of the plugs 33, the sediment in the bottom of the trap may be blown out.

The float 19 is of light weight metal not adapted to withstand external pressure. To enable it to fulfill its function I open the interior of the ball to the trap pressure through a pipe 34 which extends through a hole in the upper portion of the ball and is soldered at its beveled lower end 35 to the opposite or lower side of the ball. Such liquid as may leak into or condense within the ball is automatically expelled by variations of interior and exterior pressure. In all pressure lines, such as that in which the present trap is adapted for installation,

there are fluctuations in the pressure incident to the consumption of the pressure fluid at its point of use. It is obvious that by reason of the communication established through the pipe 34 with the interior of the float 19, the internal and external pressures tend constantly to equalize. If, however, fluid 36 has gathered in the float to a sufficient height to seal the lower opening 35 of the pipe 34, then upon the lowering of the pressure in the trap chamber, the higher pressure within the float results in expansion of the gas and the consequent expulsion of portion of the liquid through the pipe 34. Inasmuch as the jets expelled from the interior of the float are apt to disperse the condensate in a finely divided condition, in which it would be readily taken up by the gas flowing through the baffle chamber, I arrange the pipe 34 in such position that its discharge impinges against the lower surface of the drip plate 16 which thus prevents the spray from entering the air passing the baffles.

Owing to the permissibly light construction of the float, because of this self-bailing feature, the float has great buoyancy relative to its weight, and therefore may be of small size. This in turn permits body 2 to be small, light in weight, compact, and cheap to manufacture. Similarly, because of the high relative buoyancy of the float, no excessive leverage is required to operate the valve, and the lever 26 is consequently short. A light and compact construction is thus obtained.

As stated, the construction shown and above described constitutes but an illustrative embodiment of what I claim as my invention.

I claim—

1. A combined separator and trap comprising a baffle chamber and a subjacent trap, baffles in the baffle chamber, and a drip plate to which the baffles discharge, said drip plate substantially corresponding in area to the baffle chamber and serving to confine the turbulent gas flow to the baffle chamber, said drip plate having a gradual downward inclination from the intake to the outlet end of the baffle chamber.

2. In a construction of the type described, a baffle chamber having inlet and outlet ports in the upper portion of the chamber, a drip plate substantially closing the lower portion of the chamber, and baffles interposed between the inlet and outlet ports, the center of area of the passages around said baffles being below that of the inlet and outlet ports, in combination with a subjacent trap, said drip plate being downwardly inclined toward the latter in the general direction of the gas flow through the baffle chamber.

3. In apparatus of the character de-

- scribed, a baffle chamber having inlet and outlet ports, an interposed baffle plate, and a perforated deflecting screen carried by the plate, a centrally channelled drip plate carried by said baffle plate to receive and discharge the condensate from the baffle plate.
4. In apparatus of the character described, a baffle chamber having inlet and outlet ports, an interposed baffle plate having upwardly inclined gutter flanges at the lower margin of the plate, said gutter flanges being inclined downwardly transversely of the plate toward a common central discharge port.
- 10 5. In apparatus of the character described, a baffle chamber having inlet and outlet ports, an interposed baffle plate having upwardly inclined gutter flanges at the lower margin of the plate, in combination with a perforated V-shaped deflecting screen supported by said gutter flanges and faced toward the inlet port.
- 15 6. In a construction of the type described, a baffle chamber, and a subjacent trap, a drip plate substantially separating the same, a self-bailing float in the trap, a trap outlet valve operated by the float, said float having a port adapted to discharge against the lower face of said drip plate.
- 20 7. In a construction of the type de-
- scribed, a separating chamber, a float chamber, a float valve, a self-bailing float operatively connected to said float valve, a vent pipe in said float and a drip plate interposed between the outer end of said vent pipe and the separating chamber.
- 25 8. A combined separator and trap comprising a separating chamber, a float chamber, a float valve, a float for operating said valve, said float having a vent pipe leading from its exterior near the top to its interior near the bottom, and a drip plate between said float and the separating chamber, and in line with the discharge from the vent pipe.
- 30 9. A combined separator and trap having a separator chamber, a float chamber, a valve chamber and a float operated valve which in combination form a pressure tight chamber, a self-bailing float having an upwardly directed jet discharge, and means for leading liquid from the separating chamber to the float chamber, said means also serving to substantially isolate the float chamber from the separating chamber, and also to reject the jet discharge from the self-bailing float.

In testimony whereof I have signed my name to this specification.

CLARENCE A. DAWLEY.
